DESIGN FOR A PARKA JACKET

Eddie Bauer, Seattle, Wash.

Application July 26, 1941, Serial No. 102,499

Term of patent 14 years

To whom it may concern:

Be it known that I, Eddie Bauer, a citizen of the United States, residing at #3230 Lakewood, in the city of Seattle, county of King, and State of Washington, have invented a new, original, and ornamental Design for a Parka Jacket, of which the following is a specification, reference being had to the accompanying drawing, forming a part thereof.

Figure 1 is a rear view of a parka jacket showing my new design with the arms in an extended position;

I claim:

The ornamental design for a parka jacket, as shown.

EDDIE BAUER.
